UNITED STATES PATENT OFFICE

SIMON W. FARBER, OF BROOKLYN, NEW YORK, ASSIGNOR TO S. W. FARBER, INC., OF BROOKLYN, NEW YORK, A CORPORATION OF NEW YORK

DESIGN FOR A PIE-PLATE HOLDER OR SIMILAR ARTICLE

Application filed January 15, 1931. Serial No. 38,318. Term of patent 14 years.

To all whom it may concern:

Be it known that I, SIMON W. FARBER, a citizen of the United States, residing at 44 Marlboro Road, Brooklyn, in the county of Kings and State of New York, have invented a new, original, and ornamental Design for a Pie-Plate Holder or Similar Article, of which the following is a specification, reference being had to the accompanying drawing, forming part thereof.

I claim:

The ornamental design for a pie-plate holder or other similar article, as shown.

SIMON W. FARBER.
